UNITED STATES PATENT OFFICE.

OTIS A. MYGATT, OF NEW YORK, N. Y.

DESIGN FOR A PRISMATIC-GLASS REFLECTOR FOR ARTIFICIAL LIGHTS.

No. 37,982.

Specification for Design.

Patented May 1, 1906.

Application filed March 29, 1904. Serial No. 200,610. Term of patent 14 years.

To all whom it may concern:

Be it known that I, OTIS A. MYGATT, a citizen of the United States, residing at New York, in the county of New York and State of New York, have invented a new, original, and ornamental design for a Prismatic-Glass Reflector for Artificial Lights, of which the following is a specification, reference being had to the accompanying drawing, forming a part thereof.

The figure is a side elevation of a reflector embodying the design.

The reflector is composed of clear glass. The top collar is smooth, and the body is frusto-conical, having external rows of four-

sided pyramids near the base and reflecting-prisms above said pyramids and extending to the collar, as indicated by lines in the drawing.

I claim—

The ornamental design for a glass reflector, having rows of external pyramids near the base, and reflecting-prisms extending from the pyramids to the collar, as shown and described.

OTIS A. MYGATT.
